LOUIS MAXWELL POTTS, OF BALTIMORE, MARYLAND, ASSIGNOR, BY MESNE ASSIGNMENTS, TO AUSTIN McLANAHAN, OF BALTIMORE, MARYLAND.

SELECTIVE ELECTRICAL SIGNALING.

1,135,821.

Specification of Letters Patent. Patented Apr. 13, 1915.

Application filed May 7, 1910, Serial No. 559,967. Renewed April 13, 1912. Serial No. 690,659.

To all whom it may concern:

Be it known that I, Louis MAXWELL POTTS, a citizen of the United States, residing at Baltimore, in the State of Maryland, have invented certain new and useful Improvements in Selective Electrical Signaling, of which the following is a specification.

This invention relates to selective electrical signaling which, broadly considered, includes the operation of electric telegraphs, telephones or any other apparatus where it is desired to effect a series of mechanical operations by electrical signals sent over a line, and the primary object of the said invention is to provide a system of this character which shall be positive and accurate in action and at the same time comparatively simple.

26 The transmitting apparatus herein shown and described forms the subject of a divisional application hereof filed May 20, 1913, Ser. No. 768,773.

In order that my said invention may be more fully understood, I shall now describe in detail, with reference to the accompanying drawings, one specific embodiment thereof, and later point out what I claim.

In the accompanying drawings, Figure 1, 30 is a diagram of an arrangement of receiving circuits and apparatus embodying my said invention; Fig. 2, a side elevation and diagram of circuits of a form of the transmitting apparatus above referred to. Fig. 3, is a section on line 3^x—3^x. Fig. 2 looking upward, with many parts omitted. Fig. 4, a fragmentary detail plan view partly in section to show the position of one of the cams of Fig. 2, relative to its operated lever 35 when the apparatus is at rest; Fig. 5, is a section on line 5^x—5^x. Fig. 2, with many parts omitted; Fig. 6, is a top plan view of the transmitting apparatus Fig. 2, with many parts omitted; Fig. 7, a fragmentary 40 detail end elevation of the key locking mechanism shown in Figs. 2 and 3; Fig. 8, a section on line 8^x—8^x. Fig. 2, with parts removed, and looking downward; Fig. 9, a section on line 9^x—9^x. Fig. 2, with parts removed, and looking downward; Fig. 10, a fragmentary top plan view of the slotted 45 guide block and its levers; Fig. 11, an enlarged detail side elevation partly in section of the clutch mechanism of the trans-

mitter of Fig. 2; Fig. 12, an enlarged detail perspective view of one of the clutch connecting pins; Fig. 13, a top plan view of one of the relays referred to in connection with Fig. 1; Fig. 14, a diagram of combinations which may be used with my present system of signaling; Fig. 15, a diagrammatic view showing the arrangement of lugs on the selector bars shown in Figs. 5 and 6, and Fig. 16, is a diagram of the current on the line for a given signal embodying my invention.

In the following description I shall take up first the reception of the signals, and for this purpose reference will now be had to Fig. 1, of the drawings. In the specific 70 form of my invention shown in this figure, I employ two main line wires 1 and 2 which lead from a source of current at some sending station to the receiving station shown, where they are grounded. Obviously, a 75 metallic return may be used instead of the ground when desired.

In line 1 are connected the coils of a polar relay 3, while in line 2 are connected the coils of two polar relays 4 and 5, the respective tongues of the latter relays being pulled toward their back stop contacts by springs 6 and 7. The tongue of relay 3 moves between two contacts 8 and 9 connected to a split resistance 10 connected between the 80 poles of a source of direct current, and this resistance is tapped at 11, so that in a circuit leading from said point 11 to the tongue of the relay, a current will pass in one direction when said tongue engages contact 8 85 and in the other when it engages contact 9. In this circuit from tongue of relay 3 to point 11 are permanently connected in series the forward coils of eight polar relays 12 to 19 inclusive. These relays have each two 90 tongues 20—21, 22—23, 24—25, 26—27, 28—29, 30—31, 32—33 and 34—35, respectively, and a separate pair of contacts for each tongue. A simple form of one of these 95 relays is shown in greater detail in Fig. 13. 100

Resistances 12' to 19' are connected respectively in series with the front coil of each of said relays 12—19 for the purpose of preventing a transformer effect from taking place between the forward and back coils 105 of said relays. With these resistances omitted each forward relay coil would act as a short circuited secondary of a trans-

former with the restoring or back coil as the primary, and thus nullify the effect of the restoring impulse. All of the forward contacts of these relays are connected to a common wire 36 which is tapped on to circuit 11, 8-9 at wire joint 36'. These contacts are normally open. All of the back contacts of these relays are connected to a common wire 37 which taps onto circuit 11, 8-9 at the tongue of relay 19. Thus we have a shunt around all the forward coils of said relays, said shunt comprising the two wires 36 and 37 across which are bridged pairs of contacts comprising respectively the forward and back contacts of relay tongues 20, 22, 24, 26, 28, 30, 32 and 34. The tongues 20, 22, 24, 26, 28, 30, 32 and 34 of these relays are tapped on to circuit 11, 8-9 at points between front coil of each relay and that of the next following relay.

Relays 38 to 45 inclusive are the selecting relays, each of which has a single tongue and two tongue contacts. These may be polar relays of usual or any desired construction. These selecting relays are connected to the relays 12-19 as follows: The back contacts of tongues 21, 23, 25, 27, 29, 31 and 33 of relays 12-19 are connected respectively in series with the forward coils of relays 38-44 and thence all to a common return wire 46 which leads to negative of a source of local current supply as indicated. The forward coils of relay 45, however, connect to the forward contact of tongue 33 of relay 18. The forward coil of this last mentioned relay also connects to common return 46. The tongue 21 of relay 12 is connected direct to the forward contact of line relay 4. The forward contact of tongue 21 connects to tongue 23 of the next relay 13, while the forward contact of the tongue 23 connects to the tongue 25 of the next relay 14 and so on down to relay 18 which has the forward contact of its tongue 33 connected to the forward coil of selecting relay 45. The tongue 35 of relay 19 connects directly to positive of a source of local current, while its forward contact connects to negative of said source. The back coils of all the relays 12-19 and 38-45 are connected in series with a source of local current, said circuit being normally open through the forward contact and tongue of line relay 5. The tongues of both main line relays 4 and 5 are connected to positive of said source of local current. The selecting relays 38-45 may be made to operate any desired receiving mechanism, such for example, as a printing telegraph receiver, or in fact any desired apparatus which may be operated by the operation of local circuits in combinations.

In the diagram Fig. 1, I have shown as indicating a form of receiving apparatus 65 eight magnets 48-55 connected respectively

to circuits controlled by the tongues of the selecting relays. These magnets may be the eight printer operating magnets of my application for Letters Patent of the United States for telegraphy filed June 17, 1910, Ser. No. 502,785 or they may represent any other desired translating devices. Telegraph receivers operated by a plurality of magnets energized selectively in combinations are well known in the art, and I do not herein claim any of these mechanisms as a part of this invention.

If applied to a system wherein the recorders are synchronously driven, the selecting relays 38-45 may, for example, be those of the Rowland system as described in U. S. Patent No. 713,497 granted November 11, 1902 or they may be the selecting relays of the automatic telegraph forming the subject of U. S. Patent No. 942,844, granted December 7, 1909 on an application filed by me. These selecting relays may, however, be used to operate local circuits selectively for any desired purpose.

The magnet 56 represents any translating device to operate mechanism previously set by the magnets 48-55 as for example the printer spacing magnet of my application above referred to.

Normally, that is when no signals are on the line, continuous direct current is sent to line over both wires 1 and 2. This current causes relay 3 to hold its tongue normally against contact 8. Local current then passes from positive of split resistance 10 through wire 11', forward coil and tongue 20 of relay 12, wire 37, wire 11' to point 11. This current, however, does not move tongue 20 to its forward stop. The other tongues of the local relays are all normally in the positions shown in the diagram. The continuous current on line 2 during this period of no signal on the line sends tongue of relay 4 against its back stop and holds tongue of relay 5 against tension of spring 7 in engagement with its forward contact. Each signal is made up of a series of impulses sent over line 1 to effect the setting of the primary relays 12-19, and one or more selected impulses sent over line 2 to effect, in combination with relays 12-19, the operation of the selecting relays 38-45. The impulses on line 1 may alternate in polarity, or be of any character which will cause line relay 3 to vibrate its tongue between contacts 8, 9. Likewise, the selective impulses on line 2 may be of any kind so long as the impulses which operate relay 4 will not operate relay 5.

Fig. 16 shows the current on the two lines for a given signal, in which A-B represents the current on line 1, and C-D the current on line 2. In the particular case shown in this diagram it is assumed that the normal current on line 1 is positive and that on line

2 negative; but both may be negative or both positive, or current on line 1 may be normally negative and that on line 2 normally positive. Of course the coils of the line relays would be wound accordingly.

For the purpose of the present description it will be assumed that the signals are employed for telegraphic purposes and that the impulses on line 2 are sent in accordance with the system of combinations illustrated in the diagram Fig. 14. Referring to this figure of the drawings, let the zig-zag row of dots through which passes the vertical line *x*—*y* represent respectively the eight impulses *a*, *b*, *c*, *d*, *e*, *f*, *g* and *h* of a signal group on line 1. These dots then represent the eight code positions of a given signal group. The impulses on line 2 for the respective signals occupy the code positions indicated by the dots under the respective transmittable characters and other signals arranged in a horizontal row along the top of Fig. 14. For example, for the letter A two impulses would be sent over line 2 occupying the *a* and *d* positions. The signal actually shown in Fig. 16 is the letter "H" for which the selecting impulses on line 2 occupy the *b* and *e* positions. The negative current at the end D of the line C—D, Fig. 16, restores the local relays to their initial positions, and further than this forms no part of the selective combination. Each signal group terminates in this way.

Let it be assumed that the signal for the letter "H" is received. Relay 3 in line 1 then receives the group of impulses A—B, Fig. 16, and the relays 4 and 5, the current as shown at C—D, Fig. 16. The first or *a* impulse on line 1 being positive, the relay 3 will continue to hold its tongue against contact 8. Relay 4 will also not at this time operate, for there is no current on line 2. When, however, current in line 1 reverses between the *a* and *b* impulses, the tongues 20 and 21 of relay 12 go forward. Relay 12 is then out of circuit and relay 13 is in circuit. This circuit which includes the forward coil of relay 13 may be traced as follows: From point 11 of split resistance over wire 11', tongue 34 and back contact of relay 19, wire 37, back contact and tongue 22 of relay 13, forward coil of said relay 13, tongue 20 and forward contact of relay 12, wire 11' and thence to the tongue of line 55 relay 3. The tongue 20 of relay 12 is now against its forward stop short circuiting its forward coil. At the same time tongue 21 of relay 12 is against its forward stop.

Since now there is a positive *b* impulse on wire 2 corresponding to the negative *b* impulse on wire 1, the tongue of relay 4 will be sent against its forward contact. Selecting relay 39 will then receive current through its forward coil over the following circuit: Tongue of relay 4, forward contact

of said relay, tongue 21 of relay 12, forward contact of said relay, tongue 23 of relay 13, back stop of said relay, thence through forward coil of relay 39 to negative. This will cause selecting relay 39 to send its tongue 79 against its forward contact and operate translating device 49.

The engagement of the tongue of line relay 4 with its forward contact is momentary only, since it is drawn back by spring 6 as soon as the operating impulse has passed. Each succeeding reversal of current in line 1 will cause corresponding relays 13—19 to send their tongues against their forward stops and in doing so each of said relays cuts itself out of circuit, that is, its forward coil, and, cuts the next succeeding relay into circuit. The relays previously cut out in a similar way remain cut out until the general restoring impulse comes along. Therefore when the *e* impulse on line 2 is received, the reversal taking place between the *d* and *e* impulses, line 1, has caused relay 15 to send its tongues 26 and 27 against their forward contacts and the *e* impulse on line 2 has sent the tongue of relay 4 against its forward stop, thus completing a circuit from the tongue of that relay through tongue 21 and its forward contact, tongue 23 and its forward contact, tongue 25 and its forward contact, tongue 27 and its forward contact, tongue 29 and its back stop, through forward coil of relay 42 to negative, thus causing relay 42 to operate translating device 52.

At the end of the signal the normal current again passes negative to line 2. This current will not affect relay 4 since this relay is so wound that current in this direction simply tends to hold its tongue against its backstop. Relay 5, however, is so wound that this negative current sends its tongue against its forward contact, where it remains until the next signal is received. When the tongue of this relay 5 does engage its forward contact it completes a circuit which may be traced from the positive terminal of a source of local current, tongue of relay 5, its forward contact, wire 37, through the back coils of all the relays 12—19 and 45—38 to negative. Current in this circuit restores all the tongues of said relays to their backstops and this places them in condition to receive a new signal. In a similar way any of the signals in the diagram Fig. 14 may be received. The words "Space", "Line", "Back" and "Blank" indicate signals used in transmission to a page telegraph receiver which forms the subject of a separate application.

As pointed out in the general introduction to this specification, the transmitting apparatus herein shown and described forms the subject of a divisional application. Reference therefore must be had to said divisional application.

sional case for claims to the transmitting apparatus *per se*. The present case, however, contains claims for a method involving transmission and reception, and also claims which include transmitting apparatus as a part of the combination. It is therefore proper that said transmitting apparatus should be described in the present specification also. This transmitting apparatus comprises, among other parts (see Figs. 2 to 13, inclusive), a suitable support in the form of a plate 58, provided with bearings 59, 60 in which is journaled a shaft 61 which is adapted to be connected with any suitable source of driving power. In the drawing I have shown this shaft driven from a small electric motor 62 geared to it through worm gearing 63.

The shaft 61 carries among other things a sleeve 64 loose thereon. Mounted fast on this sleeve, in addition to other parts, are two cams 65 and 66. Cam 65 has four similar projections 67 and an elongated intervening space 68 (see Fig. 8), and cam 66 has three projections 69, similar to 67, and one elongated projection 70 three times as long as projections 67 and 69. These cams are so arranged on sleeve 64 that elongated projection 70 lies opposite elongated space 68, so that the two cams together divide a circle into seven equally spaced projections 67, 69 and one projection 70 three times as long. The object of this spacing will be apparent later. These cams 65 and 66 engage respectively two pivoted levers 71 and 72 which carry respectively insulating studs 73 and 74, which in turn engage two contact springs 75 and 76 secured to an insulating base 77, and movable respectively by said levers into engagement with contact screws 78 and 79 in metal bridge 80 secured to insulating base 77. Also mounted on sleeve 64 are eight cam disks 81 separated by spacing disks 82 all of which are secured rigidly together and to a cam 83, so that they form a sleeve. This cam sleeve is slidable longitudinally on sleeve 64, but is made to rotate therewith by a feather engaging an elongated slot 84 in sleeve 64. (See Fig. 11). Each disk 81 carries a cam lug 85 and these lugs are spaced spirally around the sleeve formed by disks 81-82. Each of said lugs extends over approximately one tenth of the circumference of said sleeve, as shown most clearly in Fig. 9. These cam lugs 85 are adapted at times to engage each an end of one of a series of eight levers 86, all mounted on rod 87 as a common fulcrum, the said rod being supported at its ends in bearings 88, one only of which is shown. (See Fig. 9). The heads or upper ends of these levers 86 work in individual slots in a block 89 on the base plate 58, thereby holding the upper ends of said levers against the lateral thrust to which they are sub-

jected in the operation of the device. The head of each lever 86 is provided with a cam lip 90. The lower end of each of these levers is provided with a short arm 91 to each of which is attached an individual coil spring 92, the other end of which springs are secured to a bracket 93 made fast on the base plate 58. The springs normally hold the upper ends of levers 86 out of the path of cam lugs 85. (See Fig. 9). The insulating base 77 is hollowed out for a portion of its length to receive the lower end of levers 86 and their associated parts.

Cam 83 is adapted to engage a conical cam roller 94 mounted on one end of a pivoted lever 95 which carries at its other end an insulating stud 96 adapted to engage a contact spring 97 to bring the same into engagement with a contact screw 98 on a metal bridge 99.

The sleeve made up of disks 81-82 is normally forced under tension of a spring 100 up against a collar 101 fast on sleeve 64, so that normally cam 83 does not operate on roller 94. Spring 100 is held between cam 83 and the collar of a cam 102 also fast on sleeve 64. This last mentioned cam engages one end of a bell-crank lever 103 one of the arms of which carries a stud 104 adapted to operate a contact spring 105 to bring the same into engagement with a contact screw 106 on the bridge 99; while another arm of said lever actuates certain key-locking mechanism hereinafter described. The sleeve 64 receives its motion from shaft 61 through a clutch 107, which consists among other parts of a normally rotating member 108 made fast on shaft 61, and a normally stationary member 109 fast on sleeve 64. For the details of this clutch, see Figs. 11 and 12.

The clutch member 108 is provided with annular flange 110 on which are cut radial teeth 111. The member 109 has two annular flanges 112 and 113 in which are mounted for movement transversely thereto a cam latch 114 having teeth 115 at one end adapted to engage the teeth 111, and cut away at 116 to receive the nose of a lever hereinafter described. One of the walls of the recess 116 forms a cam 117 adapted by engaging said nose to shift said latch. A spring 118 fast on member 109 presses against the end of latch 114 to force it toward member 108. The coupling of this clutch is controlled by lever 119 carrying at one end a pin 120 forming a nose adapted to engage the clutch pin 114. This lever is pivoted at 121 and forms the armature of an electro-magnet 122 made fast to the base plate 58. One terminal of this magnet is electrically connected to a contact spring 123 secured at one end to base 77. This spring 123 is adapted to normally engage a contact screw 124 on metal bridge 125, but is adapted to break

contact with said screw at times under the action of a lever 126 which carries an insulating pin 127 adapted to engage spring 123.

5 Lever 126 engages at one end the periphery of a cam 128 made fast to a collar 129 forming a part of member 130 of a clutch 131. The member 130 of this clutch including collar 129 and cam 128 are all loose 10 on shaft 61, that is, this shaft may rotate relative to said parts but the latter cannot slide longitudinally of the shaft. The loose member 130 of clutch 131 carries a coupling pin 132 (see Fig. 11) which is a duplicate 15 of pin 114 of clutch 107, and this pin (132) is adapted, as in the first described clutch, to engage teeth 133 of the member 134 fast on shaft 61, under the action of spring 135. The coupling and uncoupling of the fast 20 and loose members of clutch 131 is controlled by a pin 136 which engages cam recess 137 in coupling pin 132, and this pin (136) is carried by one end of a lever 138 made fast on a rock-shaft 139 journaled in 25 bearings 140, 141. Also mounted fast on shaft 139 is a lever 142 one end of which rests on the periphery of a cam 143 made fast to the loose member 109 of clutch 107. This lever 142 is held against cam 143 under 30 tension of a spring 144, attached to an arm 145 on shaft 139 and to the base plate 58.

The signals are formed in this apparatus by operating the levers 86 so as to bring combinations of said levers into the paths of the cam lugs 85. For this purpose I employ eight slidable pins 146 which are preferably arranged in two rows of four each and staggered as shown. The operation of these pins may be effected either 40 automatically or manually. In the embodiment of my invention herein shown this operation is effected manually by means of a keyboard and associated mechanism. This mechanism comprises in the present 45 case eight selector bars 147, one for each of said pins, mounted side by side for lateral movement. The movement of these selector bars, in the case shown, is effected by means of pivoted keys 148 having cam edges 149 50 adapted to engage cam lugs 150 on the selector bars. By arranging these lugs on said bars so as to be engaged in certain combinations by the several keys, the said bars are caused to operate said pins in these 55 nations. The manner of arranging these lugs on the selecting bars will be clear from a study of Fig. 15 which shows in side elevation four of the bars removed from the machine. These lugs are simply arranged 60 so that there will be the required number in line with each key lever to shift that one or combination of bars which corresponds to the character or other signal which the particular key lever represents. For example, the letter "A" is formed by the *a* and *d*

combinations or code positions. Therefore, the *a* and *d* bars 147 would each have a lug adapted to be engaged by the beveled edge of the "A" key lever, so that when the "A" key is operated the said *a* and *d* bars will be shifted.

Each selector bar is provided on its upper edge with a lug 151 any one of which is adapted, when its bar is operated, to engage the yoke 152 of a lever 153 which operates a 75 slidable pin 154 adapted to operate a contact spring 155 made fast at one end to insulation support 77 and in line with a contact screw 156 on bridge 125. Pin 154 carries at one end an insulating tip 157 which engages spring 155.

The keys of the keyboard, which may be of any desired number, are preferably held locked against operation during the cycle of sending each signal. This is effected in the 85 present case by providing each key with a lip 158 which is adapted to be held against movement at times by a locking bar 159 extending across all the keys and mounted at its ends on pivoted uprights 160. This locking bar is rocked so as to lock and unlock the keys by means of lever 163, one of the arms 161 of which is connected to upright 160 through link 162 pivoted to the upright 160 as at 163 (see Figs. 3, 5 and 7). 90

The signaling current is supplied in the case shown by two direct current dynamos 164 and 165, a positive terminal of one and a negative terminal of the other of said dynamos being connected together and to earth 133 as shown. Positive terminal of dynamo 164 is connected through resistances 166 and 167 to contact springs 76 and 97 respectively, while the negative terminal of dynamo 165 is electrically connected through resistances 105 168 and 169 to contact springs 75 and 105 respectively. Line 1 connects to binding post 170, on metal bridge 80, and line 2 connects to binding post 171 on metal bridge 99. One terminal of a local source of current is 110 connected to one of the terminals of magnet 122 while the other terminal of said source is connected to the binding post of spring contact 155.

The operation of the foregoing transmitting apparatus is as follows: Shaft 61 rotates continuously. Consider first the normal condition of the line when no signals are being transmitted: During this time line 1 receives positive current continuously from 115 dynamo 164 through contact spring 76, contact 79 and binding post 170. When the apparatus is at rest cams 65 and 66 always stop in such position that lever 72 rests on the elongated projection 70 so as to hold spring 120 76 into engagement with contact 79. (See Fig. 8.) Line 2 during this time receives continuous negative current from dynamo 165 through contact spring 105, contact 106 and binding post 171. Cam 102 always stops 125 130

so that its lug will be in that position (see Fig. 3) where it will cause lever 103 to hold spring 105 in engagement with contact 106. Lever 103 through arm 162 also during this time of rest holds locking bar 159 out of the paths of the lips 158 of the key levers, so that any of the keys may be operated. Next, suppose a key of the keyboard is operated. Let it be assumed that this is the key corresponding to the letter "H." The operation of this key will cause its cam edge to engage lugs 150 of two of the selecting bars 147. The selector bars thus operated will push forward two of the pins 146 corresponding to the dots in the vertical column under the letter "H" of the diagram of combinations Fig. 14. The pins thus pushed forward act on two corresponding levers 86 to place them in the path of the cam lugs 85. The selector bars 147 thus operated also actuate lever 153 causing it to act through pin 154 to effect engagement between spring 155 and contact 156 (see Fig. 6). This completes a circuit which may be traced from positive supply wire 172 through winding of magnet 122, spring contact 123, bridge 125, spring contact 155, to negative return wire 173. Magnet 122 thus being energized attracts its armature 119, thereby withdrawing pin 120 from engagement with clutch latch 114. This allows said latch to be forced under the action of its spring into engagement with teeth 111 of the constantly rotating clutch member 108. The clutch member 109 then becomes coupled to the shaft 61 and so rotates sleeve 64. This sets in rotation cams 65 and 66 and the projections on these rock levers 71 and 72, thus causing them to send springs 75 and 76 alternately into engagement with contacts 78 and 79, sending to line 1, an alternating current as shown at A-B, Fig. 16.

The rotation of sleeve 64 brings two cam lugs 85 successively into engagement with the two operated levers 86, and said cams engaging the cam noses of said levers will cause the sleeve formed by disks 81-82 to slide against tension of spring 100 once for each lug 85 which engages a lever 86. The effect of this is to force cam 83 twice against the cam roller 94 at intervals corresponding to the times of engagement of said lugs 85 with the levers 86. The effect of this is to rock the lever 95 so as to bring spring 97 twice into engagement with contact 98 at corresponding intervals, thereby sending to line 2 current as shown at C-D in Fig. 16.

When the lever 86 corresponding to the b pin sent the cam 83 into engagement with roller 94, this sent to line 2 a positive impulse, and when the lever corresponding to the e pin sent cam 83 against roller 94, this sent to line 2 a positive impulse corresponding to the e position of the code.

Before sleeve 64 completes a revolution,

cam 143 operating on arm 142 rocks shaft 139 and withdraws pin 136 from the latch of clutch 131, thus coupling the normally idle member 130 of that clutch to shaft 61. This rotates cam 128 which thereby removes its projecting lug from lever 126, thus allowing spring contact 123 break contact with contact 124, thus breaking circuit of magnet 122. The effect of this is to cause the return of pin 120 to the path of clutch latch 114, and when said latch engages said pin the latter will be withdrawn from the clutch member 108, owing to the engagement of said pin 120 with the cam surface, thus uncoupling the clutch 107 and stopping the rotation of sleeve 64, with its various cams. In like manner when any of the other keys are operated one or more pins 146 will operate a corresponding combination of positive impulses.

What I claim as my invention is:—

1. Selective signaling apparatus, comprising a plurality of electro-magnets, a plurality of circuits on which the respective magnets are operated, electrical contacts in each of said circuits, electrical contacts common to all of said circuits, means responsive to a plurality of received electrical impulses for each signal to operate all of the first mentioned contacts to partially close the operating circuits of all of said magnets, and means responsive to a given one or combination of received selected electrical impulses and adapted thereby to complete the operating circuit of those only of said magnets which correspond to that one or combination of signaling impulses selected.

2. Selective signaling apparatus, comprising a plurality of selecting relays, a plurality of local circuits each of which includes a forward coil of one of said selecting relays, electrical contacts in each of said circuits, electrical contacts common to all of said circuits, means responsive to a plurality of received electrical impulses for each signal to operate all of the first mentioned contacts to partially close the operating circuits of all of said selecting relays, and means responsive to a given one or combination of received electrical impulses and adapted thereby to complete the operating circuit of those only of said selecting relays which correspond to that one or combination of signaling impulses selected.

3. In a selective signaling system, the combination with a signaling circuit of means to send a plurality of electrical impulses over said circuit for each signal, a plurality of relays the forward coils of which are connected in series in said circuit, a plurality of said relays in the series being normally short circuited, electrical connections whereby the operation of said relays by said impulses causes said relays successively to short circuit their own coils and

nullify the short circuit around the forward coils of succeeding relays.

4. In a selective signaling system, the combination with a signaling circuit, of means to send electrical impulses over said circuit, a plurality of relays the forward coils of which are connected in series in said circuit, a plurality of said relays being normally short circuited, electrical connections whereby the operation of said relays by said impulses causes each of said relays successively to short circuit its own coil and nullify the short circuit around the forward coil of a succeeding relay, a second signaling circuit, receiving apparatuses controlled by current in said second circuit conjointly with contacts of said relays, and means to impress selected impulses on said second circuit.

5. In a selective signaling system, the combination with a signaling circuit, of means to send electrical impulses over said circuit, a plurality of relays the forward coils of which are connected in series in said circuit, each of said relays except the first of the series being normally short circuited, electrical connections whereby the operation of said relays by said impulses causes each of said relays successively to short circuit its own coil and nullify the short circuit around the forward coil of the next succeeding relay, a second signaling circuit, receiving apparatuses controlled by current in said second circuit conjointly with contacts of said relays, operated by said circuits, means to impress selected impulses on said second circuit, and means to restore all of said parts to normal after each signal.

6. In a selective signaling system, the combination with a line signaling circuit, of a main line receiver included in and operated by current in said circuit, a local circuit, means whereby the operation of said receiver sends a plurality of electrical impulses over said local circuit for each signal, a plurality of local relays the forward coils of which are connected in series in said local circuit, each of said relays except the first of the series being normally short circuited, electrical connections whereby the operation of said relays by said impulses causes each of said relays successively to short circuit its own coil and nullify the short circuit around the forward coil of the next succeeding relay, and means to impress a series of electrical impulses on said line for each signal whereby said line relay is caused to vibrate its tongue.

7. In a selective signaling system, the combination with a line signaling circuit, of a relay included in and operated by current in said circuit, a local circuit, means whereby the vibration of the tongue of said line relay between its contacts sends electrical impulses over said local circuit, a plurality of local circuits controlled by said relay conjointly with contacts of said local relays, selecting relays operated by said local circuits, means to impress selected impulses

of local relays the forward coils of which are connected in series in said local circuit, each of said relays except the first of the series being normally short circuited, electrical connections whereby the operation of said relays by said impulses causes each of said relays successively to short circuit its own coil and nullify the short circuit around the forward coil of the next succeeding relay, means to impress a series of electrical impulses on said line for each signal whereby said line relay is caused to vibrate its tongue, and means to restore said relays to normal after operation.

8. In a selective signaling system, the combination with a line signaling circuit, of a main line receiver included in and operated by current in said circuit, a local circuit, means whereby the operation of said main line receiver sends electrical impulses over said local circuit, a plurality of local relays the forward coils of which are connected in series in said local circuit, each of said relays except the first of the series being normally short circuited, electrical connections whereby the operation of said relays by said impulses causes each of said relays successively to short circuit its own coil and nullify the short circuit around the forward coil of the next succeeding relay, means to impress a series of electrical impulses on said line for each signal, a second line signaling circuit, a receiver operated by current in said circuit, a plurality of local circuits controlled by said receiver conjointly with contacts of said local relays, selecting relays operated by said local circuits, means to impress selected impulses on said second line, and means to restore all of said relays to normal after each signal.

9. In a selective signaling system, the combination with a line signaling circuit, of a relay included in and operated by current in said circuit, a local circuit, means whereby the vibration of the tongue of said line relay between its contacts sends electrical impulses over said local circuit, a plurality of local relays the forward coils of which are connected in series in said local circuit, each of said relays except the first of the series being normally short circuited, electrical connections whereby the operation of said relays by said impulses causes each of said relays successively to short circuit its own coil and nullify the short circuit around the forward coil of the next succeeding relay, and means to impress a series of electrical impulses on said line for each signal whereby said line relay is caused to vibrate its tongue, a second line signaling circuit, a relay operated by current in said circuit, a plurality of local circuits controlled by said relay conjointly with contacts of said local relays, selecting relays operated by said local circuits, means to impress selected impulses

on said line, and means to restore all of said relays to normal after each signal.

10. In a selective signaling system, the combination with a signaling circuit, of 5 means to send a plurality of electrical impulses over said circuit, a plurality of relays the forward coils of which are connected in series in said circuit, each of said relays having a plurality of sets of stationary forward 10 and back contacts and a movable tongue contact for each of said sets, a two wire shunt tapped on to said local circuit around the forward coils of all of said relays, one set of forward and back contacts of each of said 15 relays being connected in multiple formation between the two wires of said shunt, and the respective moving contacts of said sets in said shunt being tapped on to said signaling circuit at points intermediate of 20 the successive forward coils of said relays.

11. In a selective signaling system, the combination with a signaling circuit, of 25 means to send a plurality of electrical impulses over said circuit, a plurality of relays the forward coils of which are connected in series in said circuit, each of said relays having a plurality of sets of stationary forward and back contacts and a movable tongue contact for each of said sets, a two wire shunt tapped on to said local circuit around the forward coils of all of said 30 relays, one set of forward and back contacts of each of said relays being connected in multiple formation between the two wires of 35 said shunt, and the respective moving contacts of said sets in said shunt being tapped on to said signaling circuit at points intermediate of the successive forward coils of said local relays, means to impress a series of electrical impulses on the 40 said line whereby said line relay is caused to vibrate its tongue, a second line signaling circuit, a line relay connected in and operated by current in said second line circuit, a local circuit including a plurality of branch 45 circuits, the tongue and forward contact of said line relay being common to all of said branch circuits, and each branch circuit being individually controlled by the first named local relays, a selecting relay connected in and operated by each of said branch circuits, and means to impress selected electrical impulses on said second line 50 to operate said selecting relays.

12. In a selective signaling system, the 45 combination with a line signaling circuit, of a relay included in and operated by current in said circuit, a local circuit, means whereby the vibration of the tongue of said line relay between its contacts sends a plurality 50 of electrical impulses over said local circuit, a plurality of local relays the forward coils of which are connected in series in said local circuits, each of said relays having a plurality of sets of stationary forward and back 55 contacts, and a movable tongue contact for each of said sets, a two wire shunt tapped on to said local circuit around the forward coils of all of said relays, one set of forward and back contacts of each of said relays 60 being connected in multiple formation between the two wires of said shunt, and the respective moving contacts of said sets in said shunt being tapped on to said local circuit at points intermediate of the successive

forward coils of said local relays, and means 65 to impress a series of electrical impulses on the said line whereby said line relay is caused to vibrate its tongue.

13. In a selective signaling system, the combination with a line signaling circuit, of 70 a relay included in and operated by current in said circuit, a local circuit, means whereby the vibration of the tongue of said line relay between its contacts sends an alternating current over said local circuit, a plurality of local relays the forward coils of which are connected in series in said local circuit, each of said relays having a plurality of sets of stationary forward and back contacts and a movable tongue contact for each of 75 said sets, a shunt tapped on to said local circuit around the forward coils of all of said relays, one set of forward and back contacts of each of said relays being connected in multiple formation in said shunt, and the respective moving contacts of said sets in said shunt being tapped on to said local circuit at points intermediate of the successive forward coils of said local relays, means to impress a series of electrical impulses on the 80 said line whereby said line relay is caused to vibrate its tongue, a second line signaling circuit, a line relay connected in and operated by current in said second line circuit, a local circuit including a plurality of branch 85 circuits, the tongue and forward contact of said line relay being common to all of said branch circuits, and each branch circuit being individually controlled by the first named local relays, a selecting relay connected in and operated by each of said branch circuits, and means to impress selected electrical impulses on said second line 90 to operate said selecting relays.

14. A selective signaling system comprising, in combination, a plurality of electro-magnets connected in series, a variable shunt comprising a terminal connected to the beginning of said series connection and a terminal connected to the end of said series 100 connection, and taps intermediate of said series of electro-magnets movable to connect with either of said terminals.

15. A selective signaling system comprising, in combination a plurality of relays connected in series, a variable shunt comprising a terminal connected to the beginning of said series connection and a terminal connected to the end of said series connection, the tongues of the respective relays being 110 tapped on to said series connection at points intermediate of the respective relays.

16. A selective signaling system comprising, in combination, a plurality of sets of electrical contacts, conductors individual to 115 each of said sets and movable to engage either contact of the respective sets, one contact of each set connected to a movable con-

- ductor of another set, and a plurality of electro-magnets connected respectively in circuit with the remaining contact of each of said sets.
- 5 17. A selective signaling system comprising, in combination, two series of relays in one of which series a forward contact of one is connected to the tongue of another throughout the series, and the back contact 10 of each is connected to the forward coil of the corresponding relay of the other series.
- 15 18. The method of electrical signaling which consists in impressing on an electric circuit a group of similar impulses for each signal, and simultaneously transmitting a selected group of impulses differing for each signal, causing these two separate sets of impulses to conjointly operate receiving apparatus, and at the end of each signal trans- 20 mitting over the line a restoring current differing in character from either of the signaling currents, for the purpose of restoring the receiving apparatus to its normal condition to receive a fresh signal.
- 25 19. A selective electrical signaling system comprising two line circuits, step-by-step switching means operated by current in one of said circuits, switching means operated by current in the other of said circuits, and 30 a series of circuits controlled by the conjoint action of said step-by-step apparatus and the second mentioned switching means, the said step-by-step switching means being at rest except on the transmission of signals.
- 35 20. A selective electrical signaling system comprising two line circuits, step-by-step switching means operated by current in one of said circuits, switching means operated by current in the other of said circuits, the two 40 devices acting conjointly to control one or more circuits.
- 45 21. A selective electrical signaling system comprising two line circuits, a series of switches operated in step-by-step order by current in one of said circuits only, a switching device responsive to current in the other of said circuits only, and a series of circuits controlled by the conjoint action of said
- step-by-step operated switches and said switching device.
- 50 22. A selective electrical signaling system comprising two line circuits, means to impress the same number and character of impulses on one of said circuits for each signal transmitted and to impress a different combination of impulses on the other circuit for each signal transmitted, a receiving line relay operated by current in the first named circuit, a series of relays greater in number than the tongue contacts of said line relay, 60 means whereby the alternate engagement of the tongue of said line relay with its contacts operates said series of relays in step-by-step order, a series of switches operated by said relays in step-by-step order, a line 65 relay responsive to the selected signaling impulses of the second named line circuit, and a series of circuits adapted to be controlled by the conjoint action of said series of switches and said last named line relay. 70
- 75 23. The method of electrical signaling, which consists in impressing on a circuit a group of similar electrical impulses on each signal transmission for synchronizing, and simultaneously impressing on a separate circuit one or more selected electrical impulses differing for each signal, and causing these two separate sets of impulses to conjointly operate the receiving apparatus, the synchronizing impulses being impressed on the 80 line only on the transmission of signals.
- 85 24. The method of electrical signaling which consists in impressing on an electric circuit impulses for synchronizing, and impressing on a different circuit selected impulses for signaling, and causing these two separate sets of impulses to conjointly operate electrical translating apparatus, the synchronizing impulses being impressed on the line only on the transmission of signals. 90

In testimony whereof I affix my signature in presence of two witnesses.
